United States Patent Office

Des. 188,344
Patented July 5, 1960

188,344

COMBINED IGNITION AND SPARK PLUG TESTER

Ronald F. Carlson, Flint, Mich., assignor to General
Motors Corporation, Detroit, Mich., a corporation of
Delaware

Filed Oct. 12, 1959, Ser. No. 57,886

Term of patent 14 years

(Cl. D52—1)

Fig. 2

Des. 188,344

PAGE 2

Figure 1 is a perspective view of a combined ignition and spark plug tester, showing my new design;

Figure 2 is a side elevational view;

Figure 3 is a top plan view;

Figure 4 is a front elevational view, and

Figure 5 is a rear elevational view.

The undisclosed side of the tester is substantially the same in appearance as the side shown.

I claim:

The ornamental design for a combined ignition and spark plug tester, substantially as shown and described.
